DESIGN FOR A VIGIL GLASS

Frederick R. Hodges, Chicago, Ill.

Application June 8, 1945, Serial No. 119,965

Term of patent 14 years

(Cl. D36—8)

To all whom it may concern:

Be it known that I, Frederick R. Hodges, a citizen of the United States, residing at Chicago, in the county of Cook and State of Illinois, have invented a new, original, and ornamental Design for a Vigil Glass, of which the following is a specification, reference being had to the accompanying drawing, forming a part thereof.

Figure 1 is a side elevation of a vigil glass, showing my new design;

Figure 2 is a longitudinal sectional view along the lines 2—2 of Figure 1; and

Figure 3 is a transverse section along the lines 3—3 of Figure 2.

I claim:

The ornamental design for a vigil glass, substantially as shown.

FREDERICK R. HODGES.
